ROAD TREATING MACHINE

George E. Hawkins, Dummerston, Vt.

Application December 4, 1946, Serial No. 713,860

5 Claims. (Cl. 94—44)

1

This invention relates to the general class of road treating machines, and has particular relation to machines operative in the maintenance of roads of the bituminous type, although it may be employed with roads of other types, the machine being adapted to thoroughly mix and evenly distribute the bitumen and aggregates after their application to the roadbed to provide a smooth riding surface.

Under prior practice, this operation of mixing and shaping the materials has generally been done by the use of separate machines, each designed for its individual service, and while the prior practice has been more or less acceptable where the road surface is substantially smooth and even in situations where the road is provided with depressions and small broken patches, the result has been somewhat unsatisfactory. While it is possible with the prior machines to place the aggregate within such depressions or broken patches, the machines have generally been unable to provide a mixture of materials within these areas, with the result that the unmixed character of these areas provide unsatisfactory spots in the treated surface.

The present invention is designed broadly to produce the mixing and contouring operations by the use of a single machine, with such machine capable of not only properly mixing the materials in the level and even road surface areas, but also within the depressions and small broken patches so that the entire surface becomes practically finished. The mixing and contouring operations are provided during travel of the machine, with the latter formed so that the operator produces the desired effect by first advancing along a margin of the road, then returning along the opposite margin, after which the machine advances within the intermediate zone between the margins. The machine structure is such as to treat a zone of approximately six feet in width, so that such treatment will accurately condition a road of approximately eighteen feet in width. If the road is of wider width, it is necessary only to add one or more additional advancing activities to the three referred to. It has been found that the cost of thus preparing the road is practically reduced 50% as compared with the costs under prior practices.

To produce these results, my invention presents three individual formations arranged for successive dealing with the materials of the road surface. These structures have one characteristic in common, in that their direction of length extends angular to the line of draft of the ma-

2

chine, the first and second extending in parallelism, while the third extends at the opposite angle. As a result, the particles which make up the road material have a tendency to be shifted laterally automatically by the advance of the machine, thus providing for a thorough mixing of the ingredients, due to the fact that there is a tendency to a constant turning over of the particles at varying rates, so that each of the particles will be given the bitumen coating and they will gradually become positioned in the proper co-relation with each other within the road.

The first and second of these structures, which extend in parallelism, include spring teeth and are thus able to meet the conditions of the road surface, the teeth readily passing into depressions or isolated patches and are therefore given similar treatment to the level surfaces. The teeth of the first structure are spaced apart to a small extent so that a major portion of the road surface within the length of the particular structure is given desired treatment, without, however, forcing the material in front of the structure to be completely carried to the rear end thereof, the tooth spacing permitting escape of minor portions to the rear of the structure. The second structure is likewise of the spring tooth type, but presenting a materially less number of teeth, and with the free ends of the teeth arranged in groups, through the connection of a predetermined number with a plate or blade surface with the result that the second structure presents a succession of spring supported plates which are active for mixing purposes on the material which has passed by the first structure and at the same time clear the roadbed to receive the surface.

The third structure is a plate or blade which extends at the opposite angle from those of the first and second structures, the machine permitting adjustment in height as between the ends of such blade. As a result, the initial contact of the blade with the material which has been prepared by the first and second structures and which was thoroughly mixed by the latter, will be gradually advanced and also moved laterally as the machine advances, this plate serving more particularly for distributing and contouring purposes.

Hence, while the first advance along one margin of the road may tend to bring particles into the marginal zone, the third structure will restore them to the roadbed and at the same time produce the distribution and contour effect; any

excess is caused to shift along the blade sufficiently to pass beyond the rear end of the blade and be left as a residue in a central zone of the road. Since, at this time, the blade preferably extends inclined to the horizontal, the blade will tend to produce the desired camber effect on the road. Obviously, when the machine advances in the reverse direction in the other marginal zone, a similar result will be produced for that side of the road, any residue being taken to the central zone. By then adjusting the blade for a horizontal height, the third advance will cause the central zone to be smoothed out and the complete camber for the road thereby provided.

To these and other ends, therefore, the nature of which will be more clearly understood as the invention is hereinafter disclosed, said invention consists in the improved construction and combination of parts hereinafter more fully described, illustrated in the accompanying drawings, and more particularly pointed out in the appended claims.

In the accompanying drawings in which similar reference characters indicate similar parts in each of the views:

Figure 1 is a plan view of the machine in accord with the present invention;

Figure 2 is a detail elevation of a portion of the frame shown as viewed from line 2—2 of Fig. 1;

Figure 3 is a fragmentary sectional view taken on line 3—3 of Fig. 1;

Figure 4 is a view partly in section and partly in elevation taken on line 4—4 of Fig. 1 but being on a somewhat enlarged scale, the quadrant being omitted;

Figure 5 is a plan view showing the traction hitch;

Figure 6 is a fragmentary view taken on line 6—6 of Fig. 1;

Figure 7 is a fragmentary view taken on line 7—7 of Fig. 1, the view being taken in the direction of the arrows;

Figure 8 is a side elevation of the machine shown in Fig. 1;

Figure 9 is a fragmentary view partly in section and partly in perspective taken from line 9—9 of Fig. 1;

Figure 10 is a fragmentary plan view taken on line 10—10 of Fig. 8; and

Figure 11 is a fragmentary sectional view taken on line 11—11 of Fig. 1.

The machine of the present invention is formed with a skeleton frame 15 which is generally rectangular in contour but varied therefrom at points to meet the conditions of the structures being carried thereby, the frame having a vertical height of suitable dimensions, sufficient to provide for the mounting of the elements, as presently described. The front end 15a of the frame is provided with a suitable traction connection 16, to permit attachment of the machine to a suitable traction structure of any desired type, the element 16 tending to set up characteristics of the trailer structure of a tractor-trailer combination. Wheels 17 are mounted to project beyond the opposite sides of the frame and located at a point where the machine assembly is more or less balanced, the construction thus having somewhat of the characteristics of a two-wheeled trailer.

The first and second structures heretofore referred to are mounted within the frame, each

of these being mounted at an angle of approximately 45° to the line of draft.

The first structure—which is being referred to as the “leading bar”—constitutes the primary aggregate mixing unit and comprises an angle iron bar or member 18, this bar being approximately six feet in length with a general cross section of approximately three inches by three inches; if desired, it may be of hollow formation and formed of one-half inch metal. The ends of the bar have suitable pintles 18a welded or otherwise secured thereto, the latter being mounted in bearings carried by the opposite sides of the frame, the bar extending at an angle of approximately 45° to the line of draft.

The bar 18 carries a plurality of spring teeth 19 which are of the general type employed in connection with harrow service, with the exception that the free ends are blunt, each tooth being of spring metal of a desired length and curved rearwardly and downwardly, the cross sectional dimensions of each tooth presenting the width as of approximately two inches and the thickness as of one-quarter inch, being formed of high carbon spring steel. The front ends of the teeth 19 are secured to a face of the bar 18 at spaced apart distances of approximately one-half inch, by a flat bar 20, the ends of the teeth being mounted between the flat bar 20 and bar 18 and secured in position by bolts connecting the two bars.

The pintle mounting of bar 18 permits the bar to be rotated, thus enabling the teeth to be moved between a service position in which the teeth 35 yieldingly engage the road aggregate, and a raised position which is used during transportation of the machine while inactive. The two positions are controlled by lever 21 carried by bar 18 and which has its free end pivotally connected with a connection 22 carried by an operating handle 23 itself carried by the bar of the second structure, presently referred to, and which is designed to shift both structures concurrently between the service and inactive positions.

Assuming the teeth of the leading structure are in service position, the operating handle 23 will cause the teeth to be placed under a slight tension, so that a forward draft of the machine will cause the teeth to engage the layers of bitumen and aggregate, preferably creating spaced furrows within the layers with the springiness of the teeth being effective to cause them to also traverse any depressions or small patches, as well as tending to stir up the particles of the layers causing them to become coated with the bitumen material. In addition, the inclination of bar 18 will tend to cause particle movement toward the rearwardly displaced end zone of the bar, and since the teeth of the assembly are spaced apart, the portions of the layers located between teeth will pass between adjacent teeth. As a result, the advance of the machine will cause the portions of the aggregate layer in advance of the individual teeth, to be broken up into more or less individual particle members, some of which may pass to the rear of the advancing teeth through such spaces, with the ribs between furrows, the remainder passing laterally to the rearwardly disposed end of such leading structure, and into a windrow formation produced at the side of the machine, the particles thus becoming mixed and also receiving the bitumen coating.

Structurally, the second bar structure has many of the characteristics of the leading unit, and corresponding parts bear similar reference

characters. The number of teeth of the intermediate unit are greatly reduced and positioned with materially increased spacing—generally, twelve teeth are utilized with the teeth spaced a distance of approximatey six inches. Also, the free ends of the teeth carry laterally-extending blades 25, these being of suitable width and each having a length dimension such as to extend over and be secured to a plurality of adjacent teeth—generally three teeth—to thereby provide a succession of groups of teeth lengthwise of the bar with each group equipped with an individual blade; the blades are of sufficient length to provide an overlapping relation of adjacent ends of the blades of adjacent groups, thus, in effect providing a continuous flexible band in the direction of length of the unit, and with such group blades capable of yielding. Hence, the assemblage is capable of producing the admixing activities upon such ingredients as have passed through the leading unit spaces in a manner similar to that of the leading unit, excepting that the action is by group activity of blades rather than the individual teeth activity of the leading unit, in addition to which the continuity effect acts to shift all residue of the ingredients in completely admixed condition from the roadbed to the windrow formation that was begun by the leading unit, thus completely clearing the roadbed.

The lever 23 is carried by bar 18' of the intermediate unit, and has connection with the bar 18 through the connections previously described. The lever cooperates with a quadrant 24, so that both units can be rocked on their pivots concurrently and the quadrant is so arranged that with the teeth of both units in contact with the road surface they are placed under tension, thus providing for teeth and blade yielding and permitting tooth and blade entry into depressions, etc.

The second structure is designed for a dual purpose. The leading unit treats the allocated ingredients by dealing with a major portion of these through the furrow-producing activities above described. Hence a certain portion of the untreated ingredients passes through the teeth of the first unit in the form of rib-like formations. One of the purposes of the second bar and its group blade is, therefore, to admix this residue from the first unit and to carry such admixture to the windrow formation produced by the leading unit. As a result, the roadbed is thus left clear of the ingredients—with the latter in admixed form located in the windrow formation—and presents the roadbed in proper condition to serve as the base upon which the road surface is to be produced, this service being provided by the intermediate unit.

The aggregates thus shifted to the windrow formation of the marginal zone are then subjected to the action of the trailing unit which is located in rear of but connected to the frame 15.

The feature of this third structure is that of a solid blade 26 which not only extends the full width of the machine but preferably a distance beyond such width so as to provide projecting zones. The blade 26 may be, and preferably is, formed sectional in the direction of its width, with the upper section forming a support for a lower section, the latter being capable of detachment from or adjustable vertically relative to the upper section to take care of possible conditions of service. The upper section, indicated at 26a, is connected with the rear of the frame by a plurality of spaced apart lever arms secured thereto and having their forward ends supported by the

rear of the frame in such manner that each arm can be swung through an arc. The arms, indicated at 27, differ as to length, the arrangement being such that the blade 26, when in its service position will extend across the path of travel of the machine and with the direction of length of the blade at an opposite inclination to the line of draft with respect to bars 18 and 18'. Hence, as the machine advances, the aggregates which are collected in windrow formation at an end of the first and second structures will be picked up by this blade 26 and be shifted back upon the road surface, due to such angularity of the blade. And since the lower edge of the blade is continuous from end to end and is substantially straight, it is apparent that as the machine advances, the aggregates are distributed to practically a uniform depth onto the road surface, any excess passing beyond the rearward end of the blade.

The lever arms 27 differ as to length, these arms having their outer ends suitably connected with the section or blade support 26a. The opposite ends of these arms 27 are pivotally secured to the rear of frame 15, each arm having its individual pivot, but with such pivots having their axes extending in parallelism, due to the angularity of their bearing supports.

Generally, three such arms are employed, one being located in the end zone of the bar which is nearest the frame; a second extends from the opposite side zone of the frame and hence is secured to the support 26a toward the opposite end of the blade, the position, however, being more remote from the latter end of the bar than the position of the first mentioned arm relative to the opposite end of the blade. This difference is due to the fact that in view of the parallel pivot axes of the arms, the arms extend in parallelism while the blade itself extends angularly to such parallel axes. To provide a support for such end zone, an auxiliary arm 27a is secured to the inner side of support 26a adjacent such end and has its opposite end pivotally connected to the adjacent arm 27, so that both arms practically move together, in such manner as to permit proper automatic adjustment of arm 27a when the working edge of the blade has been moved into a plane inclined to the horizontal for service activity. The third arm 27 is mounted at a point intermediate the two end pivoted arms.

To provide the proper controllable movement to these arms 27, a pair of supplemental lever arms 31 are utilized, each of which is connected with a shaft 29 individual to itself, with each shaft mounted in brackets 28 carried by the rear of the frame. These arms 31 are respectively positioned above the arms 27 which approximately represent the opposite end zones of blade 26, each arm 31 being connected to its arms 27 by a link connection 32. Shafts 29, although individual, have their axes in alinement, with such axes located a material distance above the axes of the several arms 27.

Shafts 29 are shown as of extended length, this being arranged as a matter of convenience in providing the operating structures for the individual shafts. Each shaft carries an upstanding lever 33 which is operatively connected with a handle or operating lever 30 pivotally mounted on a platform 34 of the frame, the lever and handle being operatively connected by a connection 35. Since the shafts 29 are individual, separate operating connections for each are provided and the handles 30 are adapted to be co-

operative with a quadrant 36 also mounted on the platform 34. This permits individual controllable and adjusted movements of the handles.

As will be understood, the arrangement just described will permit individual adjustment of handles 39 with corresponding adjustment of the lever arms 31 through the connections described, the adjustment being carried to the arms 27 through the links 32. Since only two of the arms 27 are thus connected with the handles and these arms are widely separated, it will be understood that one arm can change the position of one end of the blade relative to the horizontal to a degree or extent different from that of the other end, thus making possible the shifting of the working edge of the blade between a horizontal position and a position in which the edge is inclined to the horizontal.

Since the platform 34 is so arranged as to permit ready operation of handle 23 therefrom, it will be understood that the operation of the entire machine is completely under the control of the operator upon platform 34, it being understood, of course, that since the machine is being drawn by a separate traction device, his control does not reach to the latter.

It can be seen, therefore, that the present machine includes three individual units supported by the frame at certain specified angles whereby the leading and intermediate units effectively and thoroughly mix the bitumen and aggregates and position such ingredients in a windrow at the side of the machine, thereby clearing the roadbed, so to speak, after which the trailing unit will move the mixed ingredients from the windrow over the roadbed in a smooth, uniform manner. This operation is automatically effected upon movement of the machine and the bitumen and aggregates are treated *in situ* after their individual application to the roadbed.

The structural features of the intermediate unit will insure that all of the particles which may have escaped through the teeth of the first unit will be subjected to the blade action of the intermediate unit to thoroughly admix such particles and move them to the windrow produced by the first unit. Furthermore, the intermediate unit will clear the roadbed of the mixture, and in view of the speed of the machine, the windrow is rapidly formed, which means that the heated bitumen retains much of its melted condition during the initial stages of the road conditioning.

The trailing unit will then immediately initiate its distributing action on the ingredients to move the mixed ingredients once again on the roadbed area being treated to provide the smooth uniform surface.

In connection with the trailing unit, it should be mentioned that as the machine is traveling one of the side margins of the road, the working edge of the blade is set at the proper angle relative to the horizontal to provide the necessary camber conformation and the thickness of the layer to be applied. Of course after the machine has traveled the desired distance, it is moved to the marginal zone at the opposite side of the road in a reversed position and a similar sequence of operation follows.

If, for example, the road is of greater width than the two marginal zones, the machine will be returned to the original starting point, again reversed and located for operation upon the intermediate zone. However, in this situation, the blade 26 is readjusted to place the working edge in horizontal position and at the proper level

through the manipulation of the levers 30. While the individual units function in the manner above indicated, it will be noted that the exposed face of the blade 26 is in a horizontal plane instead of having the sloping formation produced when conditioning the two marginal zones of the roadbed.

In situations where the width of the road is such that it cannot be effectively treated by the three steps referred to, the same steps are continued with the final advance of the machine being through the central area of the roadbed.

As will be understood, the machine structure is of simplified type, readily produced and at comparatively low cost; its weight—approximately 1000 lbs.—is sufficiently heavy to assure the desired results, but is of light-weight type as compared with the structures needed to produce the results under prior commercial practice; and is under complete control of the operator and with minimum operating costs.

While I have herein disclosed a preferred embodiment of the machine, it will be readily understood that changes and/or modifications therein may be found desirable or essential in meeting the various exigencies of service or the individual desires of a user; I therefore reserve the right to make any and all such changes or modifications therein so deemed desirable or essential insofar as the same may fall within the spirit and scope of the invention as expressed in the accompanying claims, when broadly construed.

I claim:

1. In a machine for treating a roadbed upon which bitumen and aggregates have been deposited, a wheeled frame, a support mounted on said frame and extending transversely thereof at an acute angle to the line of draft of the frame, a plurality of spaced spring teeth secured to and depending from said support for engagement with the bitumen and aggregates, a second support mounted on the frame rearwardly of the first named support and extending transversely of the frame in substantial parallelism to the first named support, a plurality of spaced spring teeth secured to and depending from said last named support, the teeth on said last named support being spaced apart a greater distance than the teeth on the first named support, a plurality of blades carried by the free end of the teeth on the second named support with a blade connecting a group of adjacent teeth, the length of each blade being such as to provide an overlapping of the ends of adjacent blades to present a flexible working edge extending throughout the length of the second named support, and an imperforate distributing member mounted on the frame rearwardly of said first and second named supports extending transversely of the frame at an acute angle opposite to the angles of the first and second named supports, the imperforate distributing member being of such length as to extend beyond the outer extremities of said first and second named supports whereby during movement of the frame along the roadbed the teeth on the first named support will admix and move a portion of the bitumen and aggregates toward one end of the first named support to produce a windrow, the residue of the bitumen and aggregates being admixed and moved by the blades on said second named support toward the windrow formed by the first named teeth, and the said distributing member being adapted to move the admixed bitumen and

aggregates from the windrow upon the roadbed in a smooth even manner.

2. A roadbed treating machine as claimed in claim 1 wherein the said first and second named supports are mounted on the frame in parallel relationship.

3. A roadbed treating machine as claimed in claim 1 wherein said first and second named supports extend transversely of the frame in parallel relationship to the frame at an angle of approximately 45 degrees to the line of draft of the frame.

4. A roadbed treating machine as claimed in claim 1 wherein said first and second named supports are pivotally mounted on the frame for movement about a horizontal axis, a linkage operatively connected with the said supports, and lever means connected with said linkage to simultaneously move said supports about their pivots.

10

5. A roadbed treating machine as claimed in claim 4 wherein said distributing member is pivotally mounted to the rear of said wheeled frame for movement about a horizontal axis, and lever means operatively connected with said distributing member to move said member.

GEORGE E. HAWKINS.
